UNITED STATES PATENT OFFICE.

ADOLPH NYDEGGER, OF MILWAUKEE, WISCONSIN, ASSIGNOR TO C. H. & E. MANUFACTURING CO., OF MILWAUKEE, WISCONSIN.

BILGE-PUMP.

1,242,231.

Specification of Letters Patent.

Patented Oct. 9, 1917.

Application filed January 24, 1917. Serial No. 144,316.

To all whom it may concern:

Be it known that I, ADOLPH NYDEGGER, a citizen of the United States, and resident of Milwaukee, in the county of Milwaukee and State of Wisconsin, have invented certain new and useful Improvements in Bilge-Pumps; and I do hereby declare that the following is a full, clear, and exact description thereof.

- 10 The present invention relates to new and useful improvements in portable bilge pumps, more particularly of that type including a diaphragm having a centrally disposed discharge valve.
- 15 It is in general the object of my invention to simplify and otherwise improve the structure, and to increase the efficiency of pumps of this nature.

More particularly, it is an important object to provide a worm gear drive means for the pump, whereby a maximum compactness of structure is procured, and further whereby a drive means may be efficiently housed.

20 25 A further important object resides in the provision of a convenient general assembly for the pump and its drive engine whereby both the pump and the engine are afforded an integral common base, and it is in this connection more specifically an object to utilize said base as portions of the engine and pump structure.

With the above and other objects and advantages in view, the invention resides 30 more particularly in the novel combination, formation and arrangement of parts hereinafter described and pointed out in the appended claims.

In the drawings:

40 Figure 1 is a side elevational view of a bilge pump and engine constructed in accordance with my invention.

Fig. 2 is a top plan view of the engine and pump.

45 Fig. 3 is a vertical sectional view through the worm drive mechanism of the pump on the line 3—3 of Fig. 2.

Fig. 4 is a vertical sectional view through the discharge valve of the pump.

50 Fig. 5 is a longitudinal vertical sectional view of the pump on the line 5—5 of Fig. 2.

Fig. 6 is a vertical section view of the inlet valve on the line 6—6 of Fig. 5.

Referring now more particularly to the accompanying drawings, both the engine A

and the pump B are mounted on a single base casting which is in turn bolted to longitudinal skid member 10 or to any suitable carrying means. This base casting comprises a top 11 and side and end walls 12 outwardly flanged at their lower edges to seat on the skids. The engine, which is generally of conventional type comprises a bed 13 bolted transversely on one end of the body casting, and a piston 14 and crank casing 15 from which projects a shaft 16 carrying a fly wheel 17 at its outer end and having a transverse head 18 at its inner end bolted to a flexible plate 19 to which is also bolted a transverse head 20 of a pump carried shaft 21, thus providing a flexible coupling to take up slight irregularities in the alinement of the shafts. At its end adjacent the engine the body casting is provided with a bottom section 22 and a transverse partition wall 23, thus forming a chamber in connection with the adjacent wall and top portions of the body casing and this chamber is utilized as the gasoline tank of the engine.

To form the intake chamber of the pump, that end of the top of the body casting farthest from the engine is provided with an opening 24 and the casting is provided adjacent the opening with depending inner wall portions 24 and a bottom 25 coacting with opposite side wall portions of the casting. One of said opposite side wall portions is apertured to receive an attaching nipple 26 which is secured thereto by bolts 27 passing through an intermediate flange portion thereof, and the other side wall portion is provided with a bleed opening 28 for the chamber. The inner end of the nipple is horizontally elongated to form a valve seat and coacting with this seat is a flexible inlet valve plate 29 secured by the screws 29' to the upper side of the seat and having stiffening and weighing plates 30 bolted to its lower portion. Secured by bolts 31 to the bed plate in registry with the inlet chamber aperture 24 is an upstanding cylindrical casing 32 from one side of which projects an outlet spout 33. The upper portion of that side of the casing adjacent the pump shaft is bifurcated to form inner and outer wall portions defining the lower portion of the gear casing 34 of the pump, and the pump carried shaft 21 which is coupled to the engine shaft is journaled in bearing 35.

ing blocks 35 bolted to the lower open ends of said casing, and closing said casing whereby its lower portion forms an oil tight well. An upper casing portion 36 is bolted to said lower portion and these casing portions form split journals for a valve actuating crank shaft 37. This shaft carries within the casing a worm gear 38 meshing with a worm 39 on the shaft 21.

10 The flexible diaphragm 40 of the pump is disposed over the aperture 24 of the body casting and is secured in place by the disposition of its edges between the cylindrical casting 32 and the body casting, whereby at 15 the same time a seal is formed for the connection of said castings. Journaled on the inner crank portion of the valve actuating shaft 37 by means of its split head portion 41 is a valve pitman 42 which extends into 20 the casing 32 and comprises divergent arms through the ends of which are passed bolts 43 passed also through upper and lower diaphragm clamping rings 44 and 45 respectively which are preferably provided 25 with outwardly inclined annular flange portions whereby to relieve strain from the diaphragm. The lower clamping ring is provided inwardly of the upper ring with an upstanding annular flange 46 and this flange 30 serves to direct the inner edge of the diaphragm upwardly when clamped between the rings to form a seat for the valve head 47. This valve head is guided in its movement by depending fingers 48 slideable within 35 the lower clamping ring 45 and by a central upstanding pin 49 slideable through a connecting bar 50 of the lower ends of the pitman arms. Disposed on this rod is a spacing sleeve 1 whereby the unseating movement of the valve head is limited.

40 From the foregoing description it is seen that an exceedingly simple efficient and compact bilge pump has been provided wherein a practically noiseless drive is procured by the worm 39 and gear 38. Attention is particularly directed to the ease and convenience with which the various parts of the pump may be assembled and disassembled, as the entire outlet valve mecha-

nism including the casing 32 may be removed by detaching the bolts 31 which secure it to the bed casting, and detaching the bolts of the flexible shaft coupling, this detachment also providing for the removal or insertion of the diaphragm. By utilizing the interior of the bed casting as portions of the pump and engine, an exceedingly compact combined structure is procured, and at the same time a proper relative positioning of the engine and pump is assured.

What is claimed is:

1. A combined engine and bilge pump structure, comprising a single bed casting having chambers formed in its end portion, an engine secured to the bed pump over one 65 of the chambers, a pump casing secured to the casting over the other chamber, said other chamber forming the inlet compartment of the pump and the first named chamber forming the fuel supply tank of 70 the engine.

2. A combined bilge pump and engine structure comprising a single bed casting having a chamber in one end, a casing secured thereto in registry with the chamber, 75 a diaphragm disposed between the chamber and casing and centrally apertured, clamping rings bolted to the diaphragm adjacent its aperture, a crank shaft extended transversely of the casing, a flexible connection 80 between the engine and crank shaft, a pitman connecting said crank shaft and rings, a valve slidably mounted within the rings, a centrally upstanding pin carried by the valve and slideable in a guide opening in 85 said pitman for guiding said valve, and a spacing sleeve disposed on said pin whereby the upward movement of the valve is limited, substantially as described.

In testimony that I claim the foregoing I 90 have hereunto set my hand at Milwaukee, in the county of Milwaukee and State of Wisconsin, in the presence of two witnesses.

ADOLPH NYDEGGER.
